CAR COUPLER CONSTRUCTION

Arthur J. Bazeley, Shaker Heights, Ohio, assignor
to National Malleable and Steel Castings Com-
pany, Cleveland, Ohio, a corporation of Ohio

Application April 6, 1932. Serial No. 603,545

15 Claims. (Cl. 213—142)

This invention relates to car couplers, and more particularly to improvements in American Railway Association standard couplers. In my co-pending application Serial No. 381,180, filed July 5 26, 1929, there is described a coupler construction which embodies improvements over the prior standard D-coupler, and which is now known in the art as the American Railway Association E-coupler. One of the features of the E-coupler 10 is the construction through which the lock engages the knuckle and it has been my object to provide for the desired cooperation not only between the improved knuckle and lock of the E-coupler, but also to enable the D-knuckle to 15 be employed in combination with the E-lock and other parts of the E-coupler, as well as for employment of the E-knuckle in combination with the lock and other parts of the D-coupler or, in short, to make the D and E-knuckles interchangeable. 20 This is important because, although the E-coupler has been adopted as standard for the future, D-couplers will be in existence for many years. Therefore, if the knuckles of the D and E couplers were not interchangeable, the railroads would find it necessary 25 to keep two different types of knuckles in stock so long as the D-couplers remained in existence. Since the knuckle is the important replacement part of couplers, it is very desirable to make this 30 part interchangeable. I have found that when an E-knuckle as shown in said application is placed in a D-head there is a tendency, with bottom and rotary lock operating mechanisms, for the anti-creep device to interfere with the desired 35 unlocking action of the parts, and by my present invention I have provided a construction which avoids this disadvantage and at the same time enables the E-knuckle to be employed in an improved manner in the standard D-head in 40 lieu of the standard D-knuckle. Other objects and advantages will be in part apparent and in part pointed out in connection with the following description of a preferred embodiment of the invention.

45 In the accompanying drawings:

Fig. 1 is a plan view of an improved coupler knuckle in accordance with the invention, showing a D-lock in engagement therewith.

Fig. 2 is a side elevation of the knuckle shown 50 in Fig. 1.

Figs. 3 and 4 are enlarged, vertical sections on the lines 3—3 and 4—4, respectively, of Fig. 1, parts of the construction being broken away.

Fig. 5 is a view similar to Fig. 1, but partly 55 broken away and showing an E-lock in engage-

ment with an improved knuckle according to the invention.

Figs. 6 and 7 are vertical, sectional views taken, respectively, on lines 6—6 and 7—7 of Fig. 5.

Fig. 8 is a longitudinal, vertical section through 60 a bottom operated coupler embodying the invention, showing the lock in locked position and the lock lifter mechanism operated a slight distance from normal position preparatory to lifting the lock.

Fig. 9 is a view similar to Fig. 3, but partly broken away and illustrating a rotary operated coupler.

Fig. 10 is a view similar to Fig. 1, but illustrating an E-lock in engagement with a 70 D-knuckle.

Fig. 11 is a section taken on the line 11—11 of Fig. 10.

Referring to Figs. 1, 2, 3, 4 and 8 of the drawings, there is shown a coupler head A, lock-lifter 75 C, lock L_D, and knuckle thrower T, all well known and employed in the standard D-coupler. The knuckle K_E is the same as that disclosed in my previously mentioned copending application except as hereinafter noted. The lock L_D has a 80 leg 2 and is supported, in knuckle-locking position, on projection 4 of the knuckle tail 5, the under side 4' of the head of the lock engaging the top of said projection 4. The center of gravity of the lock is located rearward of 85 the portion thereof in engagement with said projection 4 as a consequence of which the forward edge of the lower end of the lock leg 2 engages the built-out portion 3 of the coupler head as shown in Fig. 8. The lifter member C of the 90 standard bottom-operated uncoupling mechanism is provided with a pin 6 engaging in the usual slot 7 in the lock leg 2 as is well known in the art. It has been found that when the knuckle shown in my aforesaid application is employed 95 in a standard D-coupler having a bottom or rotary operated lock, the raising of the lock to lock-set position is frequently prevented, and this I find to be caused by the elements provided for obviating creeping of the lock. In this 100 connection, as is well understood, the head of the standard D-coupler includes a projection 9, which lies in the path of a lug 8 on lifter member C of the uncoupling mechanism when said member C is in its normal position. When the knuckle 105 of my application above referred to is employed in a D-coupler, the lock thereof is supported on the projection aforesaid of the knuckle tail, and upon operation of the member C for raising the lock it was found that the lug 8 was apt to en- 110

gage the projection 9, frequently blocking further operation of said member C and preventing the latter from lifting the lock. I have found that this difficulty may be eliminated in a simple but highly effective manner whereby the knuckle aforesaid may be employed in a D-coupler without interference with the bottom or rotary operated uncoupling mechanism. To this end I cut away part of the upper portion of the lug 4, to provide the surface shown at 10, with the result that the lock is supported from said lug in a lowered position; the slot 7 being thereby so located with respect to the projection 9 that during upward movement of the member C said slot cooperates with the pin 6 to shift the lug 8 clear of said projection. Thus, as shown in Fig. 8, the lifter member C has been raised from normal position; and the slot 7, in cooperation with pin 6, has moved the lug 8 out of the path of projection 9.

The surface 10, formed by cutting away part of the lug 4, is shown particularly in Figs. 1 and 2, and preferably slopes downwardly toward the front of the knuckle. This construction of the surface 10 aids in urging the lock as a whole forwardly when the same is in locked position, thus tending to maintain the anti-creep projection 8 in operative relation to the lug 9 as long as the element C is in its normal unoperated position. Owing to the narrow forward end of the D-lock, as shown in Fig. 1, this lock does not rest on surface 11 hereafter described.

At opposite ends of the surface 10 are portions 11 and 12 of the lug 4. When the knuckle K_E is employed in an E-coupler, as shown in Figs. 5, 6 and 7, the lock L_E thereof is supported in locked position through the engagement of its upper lateral projection 16 with the surface 15 of said knuckle. At the same time the head 17 of said E-coupler lock takes a bearing upon the above-mentioned surfaces 11 and 12 of the knuckle projection 4. It may be noted that the aforesaid lower supporting surface or shoulder of the lock of the E-coupler, as shown at 18, Fig. 5, as compared with Fig. 1, extends a greater distance transversely of the lock than does the corresponding surface 4' on the lock of the D-coupler, wherefore said surface of the E-coupler lock is enabled to bear upon the knuckle tail surfaces 11 and 12. As best shown in Fig. 6, the surfaces 11 and 12, and the respective cooperating wider surfaces 18 and 19 on the E-lock may slope downwardly away from the knuckle tail as illustrated in this view. The knuckle tail surface 55 10 also slopes downwardly away from the knuckle (see Figs. 2-4) as does the cooperating surface 4' of the D-lock. As has been above noted, the surface 12, as shown in Fig. 6, is engaged by the E-lock when the latter is mounted on the knuckle tail, and it will likewise be apparent from Fig. 3 that said surface 12 is engaged by and assists in supporting the D-lock when the latter is mounted on said knuckle tail.

It may be noted that the present construction not only obviates in a particularly effective manner the difficulty hereinbefore mentioned in connection with the cooperation between the D-lock and the E-knuckle, but also avoids the necessity of tampering with other parts of the construction which are desirable for the proper operation of the coupler. For instance, the supporting under face of the lock, which cooperates with surfaces 13 and 14 on the knuckle tail for tripping of the lock from lock-set and holding it in a position from which it can readily drop to locked

position as the knuckle is closed, is not modified; and this action of the device is not interfered with. Moreover, the functioning of the improved knuckle in the E-coupler is not impaired, for, as above noted, the E-lock may be supported on said knuckle through surfaces 11, 12 and 15 with the same results and advantages as are obtained by the supporting of the E-lock on the knuckle shown in my pending application hereinbefore referred to. When supported on said surfaces 11, 12 and 15, the lock of the E-coupler assumes the position shown in Fig. 1 of said pending application, and Figs. 5, 6 and 7 herein.

In Fig. 9 there is shown a standard rotary operated D-coupler construction. The elements A, K, L and T in this view are the same as those shown in Fig. 8, and the knuckle includes the novel features above described. I have found that the same problem is involved in couplers of this character, which have a lock lifter C' including an anti-creep projection 8', and that the problem may be solved in the same fashion as above explained; the knuckle supporting lock, through the cut-away portion of the lug 4, so that as the lifter C' moves upwardly the projection 8' is shifted out of the path of the anti-creep lug 9.

Means for operating the lifter member C or C', to effect raising of the lock and consequent uncoupling is well known in the art and need not be here described.

As best shown in Figs. 10 and 11, when the E-lock L_E is employed in combination with a D-knuckle K_D, the projection 16 on the lock is adapted, in locked position, to seat on the surface 15 of the D-knuckle, the desired engagement between the knuckle and lock being thus provided for. At the same time, the portion 17 on the E-lock does not interfere with the proper operation of the E-lock when employed with a D-knuckle. As pointed out above, the E-knuckle is capable of cooperating both with the D-coupler and lock and with the E-coupler and lock so that, in short, the construction of the cooperating supporting surfaces between the lock and the knuckle tail produces the result that either type of knuckle may be interchangeably used in either type of coupler. It will thus be appreciated that through the provision of the knuckle having upper and lower lock-supporting surfaces complementary, respectively, to upper and lower surfaces provided on the lock shown as above and below the locking face of the lock, the improved knuckle is adapted to support either the improved lock or the D-type lock, while on the other hand, the improved lock is adapted to be supported on either the improved knuckle or the D-type knuckle. This application is a continuation in part of my application Serial No. 381,180 hereinbefore mentioned.

The terms and expressions which I have employed are used as terms of description and not of limitation, and I have no intention, in the use of such terms and expressions, of excluding any equivalents of the features shown or described, but recognize that various modifications are possible within the scope of the invention claimed.

I claim:

1. In a car coupler, a lock having a leg, means engaging said leg for raising the lock to unlocked position, anti-creep means forward of said lock cooperating with the first mentioned means, and a knuckle having a tail comprising a portion for supporting said lock when in completely locked position in such relation to said anti-creep means

- as to permit free unlocking of the lock upon operation of the first mentioned means, said lock supporting portion having a forwardly and downwardly sloping surface for urging said lock forwardly toward said anti-creep means. 5
2. In a car coupler, a lock having a downwardly extending leg with a slot therein, means comprising an element having a pin cooperating with said slot for raising the lock to unlocked position, 10 means comprising a projection on said element adapted to engage a projection on the coupler head for preventing creeping of the lock, and a knuckle having a tail comprising a portion having a forwardly and downwardly sloping surface 15 for supporting said lock in completely locked position in such relation to said projection on the coupler head as to enable the projection on said element to engage said coupler head projection to prevent creeping of said lock, said parts being 20 so proportioned and arranged as to permit the projection of said element to freely pass said projection on said coupler head during operation of said element for raising the lock. 25
3. In a car coupler, a lock having a depending leg, a head having a built-out portion against which the forward edge of said leg is adapted to abut, means comprising an element adapted to engage said leg to operate the lock, anti-creep means including a projection on said element, 30 knuckle comprising an extension having a forwardly and downwardly sloping surface for supporting the lock in completely locked position in such relation to said anti-creep means as to insure effectiveness of the latter, said parts being so proportioned and arranged as to enable said element to be operated to raise the lock to unlocked position without hindrance from said anti-creep means. 35
4. A car coupler knuckle having a tail with a vertical lock-engaging face and lock-supporting means thereon lying substantially horizontally below said face, said lock-supporting means having a portion cut away for engagement by a surface of the lock for supporting said lock in lowered position in said coupler, said cut away portion sloping downwardly toward the front of the coupler. 40
5. A car coupler knuckle having a tail with a vertical lock-engaging face and lock-supporting means thereon lying substantially horizontally below said face, said lock-supporting means having a portion cut away for engagement by a surface of the lock for supporting said lock in lowered position in said coupler, said cut-away portion sloping downwardly and laterally away from the knuckle. 55
6. In a car coupler, a knuckle having upper and lower supporting portions adapted for interchangeably supporting different locks in completely locked position, the upper portion being engageable by one type of lock having a supporting shoulder complementary to said upper portion and located above the locking face of said lock, and the lower portion being engageable by another type of lock having a supporting portion complementary to said lower surface and positioned below the locking face of the lock, said lower portion being also adapted to support the first mentioned lock when engaged thereby. 60
7. In a car coupler, a lock having a plurality of supporting surfaces enabling said lock to be supported by either of a plurality of different types of knuckles in locking relation thereto, one of said surfaces being above and the other below the locking face of the lock, the upper one of said 70 surfaces being adapted to engage an upper supporting surface on the tail of either of two different types of knuckles, and complementary to said upper surface, and the lower one of said surfaces being adapted to engage a lower supporting surface on the tail of one of said knuckles and complementary to said lower surface. 80
8. A car coupler knuckle having a tail terminating in a vertical lock engaging face, lock supporting means projecting from said tail below said face, said lock supporting means having a lock supporting surface comprising forward and rearward surfaces and an intermediate surface, said forward and rearward surfaces being so arranged that when engaged by a lock having one type of engaging surface they support said lock in locked position and said intermediate and rearward surfaces being so arranged that when engaged by a lock having another type of engaging surface they support the last-mentioned lock in locked position. 85
9. A car coupler knuckle having a tail terminating in a vertical lock engaging face, lock supporting means projecting from said tail below said face, said lock supporting means having a lock supporting surface comprising forward and rearward surfaces and an intermediate surface, said forward and rearward surfaces being so arranged that when engaged by a lock having one type of engaging surface they support said lock in locked position and said intermediate and rearward surface being so arranged that when engaged by a lock having another type of engaging surface they support the last-mentioned lock in locked position, said intermediate surface being cut away relative to said other surfaces. 90
10. A car coupler knuckle having a tail terminating in a vertical lock engaging face, lock supporting means projecting from said tail below said face, said lock supporting means having a lock supporting surface comprising forward and rearward surfaces and an intermediate surface, said forward and rearward surfaces being so arranged that when engaged by a lock having one type of engaging surface they support said lock in locked position and said intermediate and rearward surfaces being so arranged that when engaged by a lock having another type of engaging surface they support the last-mentioned lock in locked position, said intermediate surface being cut away relative to said other surfaces. 105
11. A car coupler knuckle having a tail and lock supporting means thereon, said lock supporting means having a plurality of lock supporting surfaces adapted to support locks having different types of engaging surfaces, at least one of said lock supporting surfaces being adapted to function with all of said types of locks. 110
12. In a car coupler, a lock having a downwardly extending leg with a slot therein, means comprising an element having a pin cooperating with said slot for raising the lock to unlocked position, means comprising a projection on said element adapted to engage a projection on the coupler head for preventing creeping of the lock, and a knuckle having lock supporting means thereon comprising forward and rear surfaces and an intermediate surface, said intermediate and rear surfaces being so arranged that when engaged by a lock having one type of engaging surface they support said lock in completely locked position in such relation to said projection on the coupler head as to enable the projection on said element to pass freely by said coupler head. 135
13. In a car coupler, a lock having a plurality of supporting surfaces enabling said lock to be supported by either of a plurality of different types of knuckles in locking relation thereto, one of said surfaces being above and the other below the locking face of the lock, the upper one of said 140 surfaces being adapted to engage an upper supporting surface on the tail of either of two different types of knuckles, and complementary to said upper surface, and the lower one of said surfaces being adapted to engage a lower supporting surface on the tail of one of said knuckles and complementary to said lower surface. 145
14. In a car coupler, a lock having a plurality of supporting surfaces enabling said lock to be supported by either of a plurality of different types of knuckles in locking relation thereto, one of said surfaces being above and the other below the locking face of the lock, the upper one of said 150 surfaces being adapted to engage an upper supporting surface on the tail of either of two different types of knuckles, and complementary to said upper surface, and the lower one of said surfaces being adapted to engage a lower supporting surface on the tail of one of said knuckles and complementary to said lower surface. 155

projection during operation of said element for raising the lock, said forward and rear surfaces being adapted for engagement by another lock for supporting the latter at a different elevation with respect to the knuckle than that in which the first mentioned lock is supported.

13. A car coupler knuckle having a tail, spaced supporting portions on said tail so arranged that when engaged by a lock the latter is supported by 10 said portions in completely locked position, one of said portions comprising means adapted to co-operate with another portion of said knuckle tail for supporting another lock at a different elevation with respect to the knuckle than that in 15 which the first mentioned lock is supported.

14. In a car coupler, a knuckle having upper and lower supporting surfaces for supporting knuckle locking means in completely locked position, the upper surface being engageable by a 20

25 lock having a supporting shoulder complementary to said upper surface and located above the locking face of the lock, and the lower surface being engageable by a lock having a supporting shoulder complementary to said lower surface and positioned below the locking face of the lock.

15. In a car coupler, a lock having a plurality of supporting shoulders, one above and the other

below the locking face of said lock, the upper one of said shoulders being adapted when the lock 80 is in knuckle locking position to engage an upper supporting surface on a knuckle tail and complementary to said upper shoulder, and the lower one of said shoulders being adapted when the lock is in knuckle locking position to engage a 85 lower supporting surface on a knuckle tail and complementary to said lower shoulder.
